UNITED STATES PATENT OFFICE.

EDWARD K. GRIESEMER AND JOHN H. MANGER, OF READING, PENNSYLVANIA.

HARNESS ATTACHMENT.

SPECIFICATION forming part of Letters Patent No. 514,825, dated February 13, 1894.

Application filed September 19, 1893. Serial No. 485,818. (No model.)

To all whom it may concern:

Be it known that we, EDWARD K. GRIESEMER and JOHN H. MANGER, both of Reading, in the county of Berks and State of Pennsylvania, have invented certain new and useful Improvements in Harness Attachments, of which the following is a full, clear, and exact description.

Our invention relates to improvements in harness attachments; and the object of our invention is to produce a simple means of attaching a horse to the thills of a carriage, which means is especially adapted for a light harness such as is used on trotting horses, but which may also be applied to any ordinary harness.

A further object of our invention is to construct the apparatus in such a manner that it may be cheaply made, easily applied, and when adopted for use on a light harness for trotters dispenses with the breeching and traces, while when used with an ordinary harness it acts as a supplemental attachment to the thills and is a safe-guard against any accident which might occur if the breeching or one of the traces should break.

To this end our invention consists of certain features of construction and combinations of parts, as will be hereinafter described and claimed.

Reference is to be had to the accompanying drawing forming a part of this specification, in which similar figures of reference indicate corresponding parts in all the views.

Figure 1 is a perspective view of our improved attachments, as applied to a harness, horse and thills. Fig. 2 is a detail perspective view illustrating the manner of applying the attachments to an ordinary harness as an auxiliary device to guard against accident. Fig. 3 is a detail sectional view on the line 3-3 of Fig. 4, and shows the construction of the clip which is fastened to one of the thills and is adapted to connect with the breast collar and saddle; and Fig. 4 is a broken sectional plan of the said clip and its connection with the collar.

In our invention we employ a flexible clip 10, which is applied to each of the thills 11 to form a connection with the harness, as hereinafter described, and the clip is at one end,

fastened securely, as shown at 12, to a socket 13, the clip being preferably made integral with the socket, as illustrated, and the free end of the clip enters the socket, as shown at 14, its end being parallel with the side of the socket, while the body portion of the clip is of loop shape, as shown in Fig. 3, so that it may fit snugly around the thill. The clip is of spring metal, and the free end 13^a is threaded on a thumb screw or bolt 15, which extends transversely through the socket and turns therein and by turning the thumb screw the free end of the screw may be adjusted so as to clamp the clip securely to the thill. The socket 13 is provided, near its inner end and at one side, with a catch or pawl 16, which is secured to a spindle 17, this having its outer end shaped like an ordinary thumb screw so that it may be turned by the fingers, and the pawl or catch may, by means of this spindle, be thrown back against the tension of the spring 18 which normally presses the pawl into engagement with the groove 19 in the lug 20, this lug being adapted to enter one end of the socket 13 and being formed integral with or rigidly secured to a plate 21, which plate is firmly riveted to the breast collar 22 which is extended beyond its usual length and is riveted, or otherwise firmly fastened, to the saddle 23. The pawl 16 automatically engages the lug 20 when the latter is pushed into the socket 13, and it will be seen that this forms a very easy and secure connection between the breast collar 22 and shaft or thill, and that when the horse moves forward the strain comes on the lug and does not affect the pawl. When this arrangement above described is used, the vehicle is drawn by the thills and consequently the traces and breeching may be dispensed with. When the thills are to be detached from the harness it is only necessary to turn the catch or pawl 16 out of engagement with the lug 20, and the latter may then be pulled out of the socket.

When the auxiliary device is to be used as a safety attachment, it is arranged as shown in Fig. 2, that is to say, a strap 24, which is provided with an adjusting buckle 25, is secured to snap hooks 26 which are arranged at the ends of the strap and are snapped into

rings or keepers 27 which are securely fastened to the breast collar, one being secured to the collar near the front of the same and the other at a point opposite the saddle, and 5 the plate 21 is fastened to the strap instead of to the collar, while the clip 10 engages the thill, as already described.

When the auxiliary device is used, as just described, it may be easily applied to the harness by simply snapping the hooks 26 into the rings 27 and if it is not desirable to use the attachment, it may be readily taken off.

Having thus described our invention, we claim as new and desire to secure by Letters 15 Patent—

The combination, with the breast collar of a harness and a thill of a vehicle, of a spring clip to clasp the thill, one member of the clip terminating in a socket and the other member projecting into the socket, a screw to adjust the free end of the clip, a lug on the breast collar adapted to enter the socket, and a catch in the socket to engage the lug, substantially as described.

EDWARD K. GRIESEMER.
JOHN H. MANGER.
